(57) **CLAIM**

The ornamental design for a charger device, as shown and described.

DESCRIPTION

FIG. 1 is a perspective view showing a charger device; FIG. 2 is another perspective view of FIG. 1; FIG. 3 is a first elevation view of FIG. 1; FIG. 4 is a second elevation view of FIG. 1; FIG. 5 is a third elevation view of FIG. 1; FIG. 6 is a fourth elevation view of FIG. 1; FIG. 7 is a plan view of FIG. 1; FIG. 8 is another plan view of FIG. 1; FIG. 9 is a perspective view showing a first component of a charger device, shown separately from the remainder of the charger device for ease of illustration; FIG. 10 is another perspective view of FIG. 9; FIG. 11 is a first elevation view of FIG. 9; FIG. 12 is a second elevation view of FIG. 9; FIG. 13 is a third elevation view of FIG. 9; FIG. 14 is a fourth elevation view of FIG. 9; FIG. 15 is a plan view of FIG. 9; FIG. 16 is another plan view of FIG. 9;

FIG. 17 is a perspective view showing a second component of a charger device, shown separately from the remainder of the charger device for ease of illustration; FIG. 18 is another perspective view FIG. 17; FIG. 19 is a first elevation view of FIG. 17; FIG. 20 is a second elevation view of FIG. 17; FIG. 21 is a third elevation view of FIG. 17; FIG. 22 is fourth elevation view of FIG. 17; FIG. 23 is a plan view of FIG. 17; and, FIG. 24 is another plan view of FIG. 17.

The broken lines shown in the design in FIGS. 1-24 are included for the purpose of illustrating portions of the charger device that form no part of the claimed design.

1 Claim, 18 Drawing Sheets
